M. WILLINGER.
PHONOGRAPHIC RECORD ALBUM SIGNATURE.
APPLICATION FILED AUG. 11, 1919.

1,345,724.

Patented July 6, 1920.

Inventor
Max Willinger,
By his Attorney,
Geo. W. Maitz

UNITED STATES PATENT OFFICE.

MAX WILLINGER, OF NEW YORK, N. Y.

PHONOGRAPHIC-RECORD-ALBUM SIGNATURE.

1,345,724.

Specification of Letters Patent. Patented July 6, 1920.

Application filed August 11, 1919. Serial No. 316,600.

To all whom it may concern:

Be it known that I, MAX WILLINGER, a citizen of the United States, and a resident of the borough of Bronx, county of Bronx, 5 city and State of New York, have invented certain new and useful Improvements in Phonographic-Record-Album Signatures, of which the following is a specification.

My improvements relate to the type of 10 duplex envelop signatures set forth in my concurrent application No. 304,476, filed June 16, 1919, for the containing and storage of phonographic disk records in a conveniently accessible manner,—my present invention consisting in the specific construction and arrangement of parts herein described and claimed, and a distinctive feature thereof being the method of forming the duplex signature of envelops consisting 15 of independent blanks folded and united into an integral structure having a medial conjunctive spinal-hinge section by means of which each envelop reinforces the other, and the signature, considered as a whole, is 20 adapted for securement to the back or cover block of an album in the manner set forth in the aforesaid concurrent application.

In the accompanying drawings,

Figure 1, is a view of the inner face of the 30 blank from which is formed what may be designated for convenience of description as the left hand envelop of the duplex signature;

Fig. 2, is a like view of the blank from 35 which is formed the other or right hand envelop of the signature;

Fig. 3, is a view of the left hand envelop formed ready for attachment to the right hand envelop;

Fig. 4, is a view of the right hand envelop formed ready for attachment to the left hand envelop;

Fig. 5, is a view of the two envelops articulately attached and constituting the duplex signature;

Fig. 6, is a sectional detail upon an enlarged scale, and necessarily exaggerated as to thicknesses, etc., illustrating the conjunctive structure of the signature;

Fig. 7, is a diagrammatic projection, on the flat, of the parts shown in Fig. 6;

Fig. 8, is a sectional detail showing the spine of my duplex signature attached to an album back block.

My duplex signature is designed to be secured directly to an album back block B,

by means of staple tongues or equivalent mechanical expedients driven through its spine *s*, substantially as set forth in my concurrent application hereinbefore referred to, 60 or as indicated by way of exemplification in Fig. 8, of the accompanying drawings.

The envelop blanks A, and B, are duplicates of each other except that in the formation of the duplex signature they are reversed longitudinally as related to each other, so that in reality the same form of blank is available for the formation of either record pocket or envelop. Nevertheless it will facilitate understanding of the 65 construction involved if they are considered and described separately as well as jointly. Thus A, represents the blank used for the formation of what may be designated as the left hand envelop, and B, that used for the 70 formation of the right hand envelop, as hereinbefore intimated.

The blank A, is formed with the usual sight openings *a*, and upper edge finger spaces *a'*, and *a''*; and with a bottom flap *a''*, foldable on the scored line *a¹⁰*. It is also formed with the medial transverse scored line *a³*, which constitutes the outer or free edge of the envelop when the blank is folded, as well as with the other (parallel) 80 transverse score lines *a⁴*, *a⁶*, *a⁷*, and *a⁸*. The scored line *a⁴*, marks the limit of attachment margin *a⁵*, at that end of the blank while the scored line *a⁶*, in like manner marks the limit of marginal attachment at the other 85 end of the blank,—the three lines *a³*, *a⁴*, and *a⁶*, prescribing the width of pocket. The scored lines *a⁷*, and *a⁸*, represent and prescribe the width of spine fold *s*, between them. In forming the blank A, into the 90 pocket or envelop represented in Fig. 3, the first fold is made on the medial line *a³*, and the margin *a⁵*, is attached by an adhesive to the space between the lines *a⁶*, and *a⁷*, leaving the margin *a⁹*, with the spine space *s*, 95 protuberant beyond the line *a⁷*. The flap *a''*, is then folded over and attached by suitable means to the edge *a¹²*, of the opposite side of the pocket thereby forming and sealing the bottom of the latter. In this condition, represented in Fig. 3, the left hand blank A, is ready for attachment to the right hand blank B.

The latter, like unto blank A, is formed with the usual sight openings *a*, and upper edge finger spaces *b'*, and *b''*; and with the bottom flap *b''*, foldable upon the scored 110

line b^{10} . It is also formed with the medial transverse scored line b^3 , which coincides with the outer or free edge of this envelop when the blank is folded, as well as with 5 other parallel transverse score lines b^4 , b^6 , b^7 , and b^8 . The scored line b^4 , marks the limit of attachment margin b^5 , at that end of the blank, while the scored line b^6 , in like manner marks the limit of marginal attachment at the other end of the blank,—the three lines b^3 , b^4 , b^6 , prescribing the width of pocket. The scored lines b^7 , and b^8 , represent and prescribe the width of spine s , between them. In forming the 10 blank B, into the pocket or envelop represented in Fig. 4, the first fold is made on the medial line b^3 , and the margin b^5 , is adhesively attached to the corresponding space between the lines b^6 , and b^7 , leaving 15 the margin b^9 , with the spine space s , protuberant beyond the line b^7 . The flap b'' , is then folded over and adhesively attached to the edge b^{12} , of the opposite side of the pocket, thereby forming and sealing the bottom of the latter. In this condition, as represented in Fig. 4, the right hand blank B, is ready for attachment to the left hand blank A.

To permanently incorporate the two independently complete envelops thus formed into a unitary structure they are adhesively attached to each other between the line a^4 , and a^9 , of the blank A, and the corresponding line b^4 , and edge b^9 , of the blank B, resulting in the duplex signature shown in Fig. 5.

This conjunctive structure of parts is illustrated roughly in Fig. 6, presuming that due allowance is made for the unavoidable 40 exaggeration of thickness of material; it being understood that the blanks are made of relatively thin but tough, tenacious, flexible material, such as Manila paper or the equivalent thereof. Thus by reference to 45 this Fig. 6, as well as to Fig. 7, it will be seen that the spine s , is two ply, while the adjacent parts are three ply. That is to say, the overlap of the parts of the blank A, between lines a^8 , and edge a^9 , and the 50 corresponding overlap of the parts of the blank B, between the line b^8 , and the edge b^9 , afford an additional thickness or ply of material, on either side of the spine s —the object of which is not only to strengthen 55 the conjunctive medial spinal hinge section of the duplex signature as a whole, and prescribe the lines of envelop articulation to coincide mainly with the edges a^9 , and b^9 , but also to use the latter as a means for re- 60 inforcing the inner edges of the pockets as prescribed by the coincidental lines a^4 , and

a^6 , and b^4 , and b^6 , respectively, so as to resist the tendency of a record disk to strain and pry apart the inner walls of the pockets along these lines, as will be understood by 65 reference to the dotted lines d , d , in Fig. 5, representing record disks,—it being remembered in this connection that the outer edges of the pockets are formed by a fold of the material itself on the lines a^3 , and b^3 , respectively, and so are well adapted to resist the strain to which they may be subjected by record disks, while the bottoms of the pockets are sealed by the flaps a'' , b'' , in a like manner. In other words, the inner edges 70 of the pockets are prescribed, not by a fold of material, like the other edges thereof, but simply by the adhesion of parts along the lines a^4 , a^6 , and b^4 , b^6 , and for this reason particularly I reinforce these lines by means 75 of the marginal edges a^9 , b^9 , of both blanks. These edges also, as before intimated, tend to limit and prescribe the line of flexure or articulation of the pockets or envelops as 80 related to the conjunctive structure of the 85 duplex signature.

It may be noted that the extension of each blank beyond the pocket lines constitutes a spinal hinge section of which the spine s , is the central portion; and that these extensions are on the right of the left hand blank and on the left of the right hand blank so that when that of the right hand envelop is superposed upon and adhesively attached to that of the left hand envelop we have 95 the correlation of extension parts illustrated in Figs. 6 and 7.

What I claim as my invention and desire to secure by Letters Patent is,

1. A duplex signature for phonographic 100 record albums of the character designated, consisting of independently formed record envelops, each having a spinal hinge extension overlapping and adhesively secured to that of the other, for the purpose described. 105

2. A duplex signature for phonographic record albums of the character designated, consisting of independently formed record envelops, each having a spinal hinge extension overlapping and adhesively secured to 110 that of the other, each of said extensions being formed with a medial spine portion and with an edge flap portion beyond the spine portion so that the conjunctive structure is three ply between said spine and the 115 inner edge lines of the pockets, for the purpose set forth.

MAX WILLINGER.
